UNITED STATES PATENT OFFICE

EDWARD T. WILLIAMS, OF PELHAM MANOR, NEW ROCHELLE, NEW YORK

WATER COOLER DRIP BASIN

Application filed October 7, 1930. Serial No. 486,928.

This invention relates to mechanically refrigerated water coolers and specifically to an adjustable drip basin for such coolers.

Water coolers previously constructed included fixed drip basins which did not permit the filling of a pitcher or other larger vessel from the faucet than was intended to be used for drinking purposes without the spilling of the water on the floor.

10 It is an object of this invention to provide an adjustable drip basin which may be swung out of the way to one side of its normal position when it is desired to fill a pitcher or the like container.

15 In the drawings:

Fig. 1 is a front elevation illustrating one application of the invention; and

Fig. 2 a similar fragmentary view of a modified construction.

20 Referring to Fig. 1 of the drawings, a water cooler cabinet 10 supports a bottle of water 11, which is refrigerated by mechanical means not shown and from which cabinet cold water is adapted to be dispensed from a faucet 12. Beneath the faucet 12 is swivelly mounted a drip basin 13, provided with a depending hub 14, which projects downwardly into the drain pipe 15, fixed in position by means of an upper bracket 16, and a lower elbow bracket 17. The depending hub 14 of the drip basin fits loosely within the upper end of the drain pipe 15 and permits the drip basin to be swung around from beneath the faucet 12.

25 In order to brace the drip basin, a bracket 18 has its upper end attached in any desired manner as for example by welding or the like to the underside of a depending flange 19 of the drip basin and the lower end of said bracket is

30 provided with a collar 20, which fits loosely about the drain pipe and rests upon a collar 21 fixed to the drain pipe and forming a bearing support for the collar 20. A clip 22 may be provided for maintaining the drip basin in operative position beneath the faucet 12.

35 Referring to Fig. 2, the cabinet 10 and faucet 12 are provided with mechanically refrigerated means not shown, the same as in Fig. 1. However, instead of the stamped

or pressed metal drip pan 13 of Fig. 1, a cast drip pan 23 is employed and is also provided with a depending hub 24 which projects downwardly into the bell-portion 25 of an angularly disposed drain extension 26 of a drain pipe 27. The upright drain pipe 27 as in Fig. 1 is mounted toward one side of the cabinet from the faucet 12 and has its lower end swiveled in an elbow bracket 28 and its upper end extending through and rotatable in a bracket 29. A collar 30 is fixed on the lower end of the upright drain pipe 27 to form a bearing for the upright pipe on the elbow 27. The upright pipe also extends through an extension or lug 31 on the basin 23.

40 The construction thus described permits the drip basin to be rotated about the upright drain pipe 27 as an axis to permit the swinging away of the drip pan so that a bottle or other large container may be filled from the faucet 12.

45 It will be obvious to those skilled in the art that various other changes may be made in the construction and arrangement without departing from the spirit of the invention and therefore the invention is not limited to what is shown in the drawings and described in the specification but only as indicated in the appended claims.

50 I claim:

55 1. A water cooler comprising a cabinet, a faucet for discharging water from the cabinet, a pair of brackets mounted on said cabinet to one side of the faucet, a drain pipe mounted between said brackets, a swivelly mounted drip basin carried on the upper end of said drain pipe adapted to be normally disposed beneath the faucet but swingable away from such position to permit a larger vessel to be placed beneath the faucet, means for fastening the drip basin in fixed position beneath the faucet, and a supporting member for the drip basin connected to the drain pipe and inclined upwardly into engagement with the drip basin.

60 2. A water cooler comprising a cabinet, a faucet for discharging water from the cabinet, a pair of brackets mounted on said cabinet to one side of the faucet, a drain pipe

mounted between said brackets, a swivelly mounted drip basin carried on the upper end of said drain pipe adapted to be normally disposed beneath the faucet but swingable 5 away from such position to permit a larger vessel to be placed beneath the faucet, and means for fastening the drip basin in fixed position beneath the faucet.

3. A water cooler comprising a cabinet, a 10 faucet for discharging water from the cabinet, a pair of brackets mounted on said cabinet to one side of the faucet, a drain pipe mounted between said brackets, a swivelly mounted drip basin carried on the upper end 15 of said drain pipe adapted to be normally disposed beneath the faucet but swingable away from such position to permit a larger vessel to be placed beneath the faucet.

4. A device of the class described comprising 20 upper and lower spaced supports, a drain pipe swivelly mounted in said supports, a swivelly mounted drip basin having a discharge outlet communicating with said drain pipe, said drip basin having a portion disposed axially of said supports and having a 25 member carried by the drain pipe and extending laterally into engagement with the drip basin to form a lateral support.

In testimony whereof I affix my signature.

30 EDWARD T. WILLIAMS.
